UNITED STATES PATENT OFFICE.

HERBERT W. CRANE, OF CHICAGO, ILLINOIS.

MULTIPLE SWITCH.

1,322,545.

Specification of Letters Patent. Patented Nov. 25, 1919.

Application filed August 16, 1917. Serial No. 186,521.

To all whom it may concern:

Be it known that I, HERBERT W. CRANE, a citizen of the United States, residing at Chicago, in the county of Cook and State 5 of Illinois, have invented certain new and useful Improvements in Multiple Switches, of which the following is a specification.

My invention relates to electric switches and particularly to a multiple switch such 10 as used in the construction disclosed in my Patent No. 1,290,718, operating means for doors, dated Jan. 7, 1919.

An object in the construction herein disclosed is to provide a self-contained pre- 15 determined limit switch adapted to successively perform certain operations in timed relation to a motor driven device. The number of actuations or operations performed by the mechanism is immaterial.

20 A further object is to provide means in connection with a switch of this sort for adjusting and controlling the permitted limits of operation.

The invention will be more readily un- 25 derstood by reference to the accompanying drawings, wherein:

Figure 1 is a longitudinal vertical section through a switch constructed in accordance with my invention, the section being taken 30 on line 1—1 of Fig. 2;

Fig. 2 is a sectional view on the line 2—2 of Fig. 1; and

Fig. 3 is a sectional view on line 3—3 of Fig. 1.

35 The device comprises a casing 10 and a base member 11. Mounted within the casing and base-plate in suitable bearings 12, 13, is a shaft which is adapted to be rigidly secured to the motor driven part to be controlled. The shaft comprises the reduced end portions 14, 15, a portion of slightly increased size 16 which carries a sleeve 17, and an intermediate threaded portion 18 which supports a reciprocating nut 19. The 40 nut has an upwardly-projecting portion 20, best shown in Fig. 3, which occupies a slot 21, formed in a frame, best shown in Fig. 1. This frame comprises cylindrical end portions 22, 23, which fit over the cylindrical sleeves 24, 25. The inwardly-projecting peripheral flange 26 on the part 25, has a bearing on the enlarged portion of the

shaft. At the opposite end the corresponding inwardly-projecting flange 27 bears on the sleeve 17, which fits over the reduced portion 16 of the shaft. The frame which comprises the cylindrical ends 22, 23, and the intermediate arcuate connecting web 28, is rigidly connected to the sleeves 24, 25, by means of set-screws 29, 30. The inner portions of the sleeves 24, 25, are threaded and accommodate the threaded male portions or plugs 31, 32. The enlarged heads of these plugs are adapted to accommodate a spanner wrench or similar tool for adjusting the same longitudinally. When properly adjusted the set-screws 29, 30, are employed for securing them in adjusted position. These plugs serve to define the permissible longitudinal reciprocation of the nut 19. The parts just described are firmly held in position by means of the nuts 33, 34, which engage threaded portions of the shaft at a point contiguous to the enlarged portion thereof.

75 It will be seen from the description thus far that the shaft is freely rotatable without imparting movement to the frame or adjusting nuts. However, the switches which control the operation of the different elements 80 are actuated by rotation of the frame and this rotation is effected in the following manner. It will be understood that the frame and associated parts are maintained in a fixed position by reason of the spring 35, the ends of which overlap parts of a lug 36 formed as a backwardly-bent hook on the cylindrical end 23 of the frame. The ends 37 of the spring lie on opposite sides of a lug 38, mounted on the shell. Thus the 85 frame and its associated parts are held in a fixed position, but are permitted to rotate in either direction against the resistance of the spring. The resistance offered by the nut 19, to the rotation of the shaft is not 90 sufficient to overcome the resistance of the spring and thus the nut 19, is caused to reciprocate in a straight line. When, however, the nut has traveled to the limit permitted by the plugs 31, 32, it is jammed 95 against the same and all the parts then rotated in unison. The switch members are 100 caused to be actuated in this manner. Mounted upon the cylindrical end portion 22

of the frame is a cam plate 39, shown in section in Fig. 1, and in elevation in Fig. 2. This plate has freedom for limited angular movement relative to the frame to the extent 5 of the arcuate slot 40, best shown in Fig. 2, with which a pin 41, carried by the cylindrical portion 22, engages. Thus the frame, as it is rotated by the nut 19, is permitted a certain degree of movement before movement 10 is imparted to the cam plate. Three contacts 42, 43, 44, are controlled by the cam plate 39. Mounted on the inwardly extending portion of the bearing member 13 is a second cam plate 45. A spring 46, mounted 15 similarly to the spring 35, serves to retain the cam member 45 in a relatively fixed position. The two ends 47 of the spring, as best shown in Fig. 2, are overlapped and lie on opposite sides of a lug 48, which projects 20 from the upper edge of the cam member 45. The ends also lie on opposite sides of a pin 49, which is fixed in the base. A pair of pawls 50, are pivoted to the cam member 45, the ends of the pawls normally lying in 25 spaced relation to a lug 51 carried by the cam member 39. The lug 51, and the pawls serve as the means of connection between the cam member 39, and the cam member 45. As the cam member 39 is rotated, the lug 30 will contact one of the pawls 50, and carry the cam member 45 along until the opposite end 52 of the pawl contacts with a projection 53, from the base member, whereupon the pawl will be tripped and the cam member 45 35 will return to its original position. The first motion of the cam member 45 is without effect. However, as it continues the cam 54, formed by notching the periphery of the cam 45, will contact with the projection on 40 the spring tongue 55 and break the contact 56. Continued rotation of the cam member 45 will cause the projection to contact one or the other of the cams 57, thus forcing the spring contact member downwardly and 45 making the contact 58.

The rotation of the frame and connected parts, due to the jamming of the nut 19, will, due to the operation of the cam members referred to, cause the stoppage of the motor 50 and consequently the interruption of operation of the shaft. The circuits controlled by the switch by means of which the described results are obtained are specifically shown and described in my co-pending application 55 heretofore referred to. Upon the reversal of operation of the motor, the shaft which carries the nut will be rotated reversely and the nut and associated parts will be carried around with it. This will continue until the 60 projection 20 on the nut contacts one or the other of the lugs 59, 60, whereby the nut will be forced free, the rotating parts will be properly centered by the action of the spring 35, and the nut is free to travel oppositely

to the other limit of its movement when the 65 motions described are repeated.

I claim:

1. In a switch, the combination of a threaded shaft, a frame mounted thereon, a nut engaging the shaft and guided in said frame, 70 spring means for retaining the frame in a centered position, a cam rotatably mounted on the frame, a stop carried by the frame and adapted to limit the rotation of the cam on the frame, a second cam rotatably mounted 75 on the shaft, means carried by said first mentioned cam for causing rotation of said second cam with the first cam, means permitting the return of the second cam to its normal position prior to the return of the 80 first cam to normal position, and electrical contacts controlled by said cams, substantially as described.

2. In a device of the class described, the combination of a casing having stops, a shaft 85 rotatably mounted in the casing, said shaft having a threaded portion, a nut carried on said threaded portion, said nut having a portion adapted to contact said stops in certain positions of the nut, a frame having 90 a slot adapted to be occupied by a portion of said nut to normally prevent the rotation of said nut, adjustable jam nuts carried by said frame and located at the predetermined limits of travel of said nut, said 95 frame being adapted to be rotated by the jamming of said nut against one of said jam nuts, said stops serving to disengage the nut from its jammed position upon reversed rotation of the shaft, substantially as described.

3. In a switch, the combination of a shaft having a threaded portion, a nut mounted on the threaded portion, a frame adapted normally to prevent the rotation of said nut, 105 spring means for retaining said frame in normal position, a projection carried by the frame, a cam member having an arcuate slot co-operating with said projection whereby said cam member is permitted certain limited freedom of movement, contact members controlled by said cam, a second cam, spring means for retaining said last named cam in centered position, means carried by said frame for engaging said second cam to cause rotation thereof with the frame, and means for disengaging said second cam from the frame and permitting the return of the second cam to a normal position independently of the return of the frame, substantially as 110 described.

4. In an electrical switch, the combination of a threaded shaft, a frame mounted thereon with freedom for limited angular movement, a nut engaging the frame and adapted to cause said limited angular movement at the extreme positions of said nut, a cam member, contacts controlled thereby, spring

means for normally retaining said cam member in a centered position, means carried by the frame and cam for causing the cam to move with the frame in either direction of rotation, and means for disengaging the cam from the frame before said frame has reached its limit of rotation whereby said

cam is permitted to return to its original position, substantially as described.

Signed at Chicago, Ill., this 14th day of 10 Aug., 1917.

HERBERT W. CRANE.
